E. L. BAILEY,
PAPER RECEPTACLE,
APPLICATION FILED AUG. 6, 1918.

1,289,359.

Patented Dec. 31, 1918.

Inventor:
Edward L. Bailey,
By Chas. N. Butler
Attorney.

UNITED STATES PATENT OFFICE.

EDWARD L. BAILEY, OF MORRISVILLE, PENNSYLVANIA.

PAPER RECEPACLE.

1,289,359.

Specification of Letters Patent. Patented Dec. 31, 1918.

Application filed August 6, 1918. Serial No. 248,512.

To all whom it may concern:

Be it known that I, EDWARD L. BAILEY, a citizen of the United States, residing at Morrisville, in the county of Bucks and State of Pennsylvania, have invented certain Improvements in Paper Receptacles, of which the following is a specification.

My invention is an improved expandible paper receptacle adapted to be formed by folding or plaiting a single sheet of material and to be closed by a string. The primary object of my improvements is to provide a sanitary container for liquids, particularly for the delivery of milk, but also for solids, that is simple, inexpensive, efficient, readily closed and readily handled. The paper used is preferably opaque to prevent the action of light on its contents, light in weight, with sufficient toughness to permit its ready manipulation, and sufficiently inexpensive to admit of its being discarded without substantial loss after a single use.

The receptacle may be used alone or may contain a form for maintaining it expanded, particularly when made of quite light material.

The characteristic features of my improvements are fully disclosed in the forms embodying the same as set forth in the following description and the accompanying drawings in illustration thereof.

In the drawings, Figure 1 is an elevation of a receptacle embodying my improvements; Fig. 2 is a view of the same with parts broken away to show the character of the plaits and the use of an interior shell; Fig. 3 is an elevation of a modified construction; and Fig. 4 is a sectional view taken on the line 4—4 of Fig. 3.

The receptacle, as illustrated in Figs. 1 and 2, comprises an integrally formed bottom 1, body 2, top 3 and neck 4, produced by creasing and plaiting a single sheet of paper. The approximately circular or polygonal bottom 1 meets the body 2 at the line 1' where the material is creased; the body comprises the spiral folds or plait 2' of gradually increasing width from the bottom to the top 3; the top comprises the spiral

50 folds or plaits 3' of gradually increasing width from the creased line 2'' marking the juncture with the body to the creased line 3'' marking its juncture with the neck 4, and the neck comprises the spiral folds or plait 4'. A string 5 provides simple and satisfactory means for holding the neck closed.

The construction permits the neck, top and body to be opened readily to a convenient extent for the introduction and removal of the contents of the receptacle.

As illustrated in Fig. 2, a shell 6, which is in this instance a paper tube open at both ends, may be used to hold a light construction to form.

As illustrated in Figs. 3 and 4, the receptacle has a rectangular bottom 7, body 8 of rectangular cross section, and top 9 tapering from the body to a neck 10. The body, which is of the approximate form of an inverted pyramidal frustum, comprises the 70 oppositely disposed and overlapping side folds or plait 8'; the top comprises the spiral folds or plait 9'; and the neck comprises the spiral plait or folds 10'; the construction being closed by a string 11 and 75 being expandible to permit the insertion and removal of its contents.

As illustrated in Fig. 4, the receptacle may contain a pail 12, which is shown as a knock down construction made of a single 80 sheet of comparatively stiff paper, comprising a bottom 12^a and the sides 12^b formed by the oppositely disposed folds 12' interlocked with the folds 8', the pail serving to keep a light construction in form and to 85 hold the contents.

It will be understood that each of the receptacles shown can be shipped in collapsed, flat form, if desired, and erected as required.

Having described my invention, I claim:

1. A paper receptacle comprising a bottom, a plaited body integrally connected therewith, a plaited top connected with said body, and a plaited neck connected with said top.

2. A receptacle formed of a single sheet of paper and comprising a spirally plaited body and a spirally plaited top.

3. A receptacle formed of a single sheet of paper and comprising a spirally plaited top and a spirally plaited neck.
4. A receptacle formed of a single sheet of paper, said receptacle having a plaited body and a neck adapted to be closed by a string, in combination with a shell disposed within said body.

5. A collapsible paper receptacle formed of a single sheet of paper and comprising a 10 plaited body and a neck adapted to be closed by a fastener.

In testimony whereof I have hereunto set my name this 1st day of Aug., 1918.

EDWARD L. BAILEY.
